THERAPEUTIC INSTRUMENT FOR ALIGNING THE HUMAN BODY

Joseph A. Berg, Arcadia, Calif.

Application January 13, 1959, Serial No. 54,154

Term of patent 7 years

(Cl. D83—1)

Fig. 1 is a perspective view of a therapeutic instrument for aligning the human body showing my new design;
Fig. 2 is a front elevational view thereof;
Fig. 3 is a rear elevational view thereof;
Fig. 4 is a right side elevational view thereof; and
Fig. 5 is a plan view thereof.

The left side (not shown) is substantially the same in appearance as the right side.

The essential features of the design reside in the portions shown in full lines.

I claim:

The ornamental design for a therapeutic instrument for aligning the human body, substantially as shown and described.
